CONDUCTOR ROLL

Earll R. Muddiman, Wilkinsburg, and William E. Winterhalter, Mount Lebanon, Pa., assignors to Carnegie-Illinois Steel Corporation, a corporation of New Jersey

Application August 28, 1943, Serial No. 500,418

10 Claims. (Cl. 204—209)

1

The present invention provides a conductor roll for use in conjunction with electrolytic processes, which roll is resistant to chemical attack by the electrolyte used in such processes, whether they be cleaning processes, where a metallic body, such as a metal strip, for example, a steel strip, is conveyed through the electrolyte by the roll, in which electrolyte the strip is subjected to a cleaning operation, such as an anodic cleaning, for example, or where the strip is being conveyed through the electrolyte as a cathode for receiving a deposit of metal electrolytically thrown out of solution by the action of a metal depositing current.

One object of the present invention is to provide such a conductor roll with a surface which is resistant to wear and corrosion and thereby protects the strip from undesired effects, as will be pointed out in particularity hereinafter.

A further object of the present invention is to provide an improved conductor roll construction of increased strength and electrical conductivity and which is provided with improved instrumentalities for effecting an efficient circulation of cooling water within the interior of the roll to prevent overheating of the roll.

Other objects and advantages will become apparent as the description proceeds, and the features of novelty will be defined in particularity in the appended claims.

The invention will be understood more readily by reference to the accompanying drawings, wherein:

Figure 1 is a diagrammatic showing of a portion of a commercial electroplating line for electroplating a continuously rapidly moving metal strip, the plating line having the improved rolls of the present invention associated therewith;

Figure 1A is a continuation of the equipment of Figure 1, the view showing the completion of the said equipment;

Figure 2 is an enlarged view of a portion of the plating unit shown in Figure 1, showing in greater particularity the disposition of the improved rolls relative to the plating unit, the view being in longitudinal sectional elevation;

Figure 3 is a transverse sectional elevation through the unit of Figure 2, the view being taken on the line III—III of Figure 2, looking in the direction of the arrows;

Figure 4 is an enlarged view of the top portion

2

of the apparatus of Figure 3, showing details of the mounting of the improved roll of the present invention;

Figure 5 is a side elevation of the improved roll of the present invention, together with associated parts;

Figure 6 is a longitudinal sectional elevation of the improved roll of the present invention, showing details of construction; and

10 Figure 7 is a transverse sectional elevation of the roll taken on the line VII—VII of Figure 6, looking in the direction of the arrows.

The conductor roll of the present invention will be described with particular reference to its 15 adaptation for use in conveying a ferrous metal strip through an electrolytic tin-plating line, and for rendering the strip itself electrically energized as it moves through the tin-plating apparatus, although it will be understood that the 20 invention is not necessarily so limited.

When ferrous metal strip is to be coated electrolytically, such as, for instance, with tin, the strip after annealing and tempering, is subjected to a series of processing steps wherein the surface 25 thereof is provided with a coating which is uniform and tightly adherent thereon, and in which the physical properties imparted to the base metal remain unchanged.

With reference to Figures 1 and 1A, there is 30 shown by way of illustration, a diagrammatic arrangement of various processing steps, as related to the coating operation in which the improved conductor roll of the present invention is employed.

35 Referring to these views, coils S of strip steel to be processed are shown as disposed on unreeling devices. Two or more of such unreeling devices are provided so that as the end of the strip being processed approaches, a new coil is already 40 positioned so that its front end can be joined to the rear end of the outgoing strip, thereby providing continuity of the processing through sequential steps to be described subsequently herein. The strip S is shown as being passed through a feed in device 2, a shear 3, a welding apparatus

45 4, and a pair of feed-in pinch rolls 5, which pull the strip from the unreeling device and direct it into the looper pit 6. The feeding device 2, shear 3, and welding apparatus 4, serve only the function of correctly positioning and joining the ends

of the outgoing and incoming strip so that passage of the strip through the subsequent processing steps is substantially continuous.

From the looper pit, the strip is pulled through roller side guides 7 which laterally position the strip so that it is in proper position to pass through the subsequent processing apparatus. The strip then passes through a tensioning device 8, wherein back-tension is created of a magnitude only sufficient to hold the strip taut as it passes through subsequent apparatus. From the tension device 8, the strip is passed into and through a vertical pickling tank 9 in which the surface of the strip is conditioned by subjecting it to an initial vigorous anodic pickling action followed immediately thereafter by a straight chemical attack by the acid pickling medium contained therein. Upon emerging from the pickling tank, the steel strip is passed into and through a rinsing and scrubbing machine 10 which removes foreign matter and residual pickling solution from its surface.

The strip now enters the plating unit 12, which may comprise a vertical tank having upper conveying and conductor rolls 12a, of the construction of the present invention, and lower sink rolls 12b, the combined conveying and conductor rolls 12a and the sink rolls 12b being so positioned with respect to each other as to maintain the strip in a vertical position in its travel through the several vertical passes provided in the said tank. The strip is established as cathode in the plating tank by its passage over the conveying and conductor rolls 12a which are connected through suitable means, not shown, to the negative side of a plating generator, not shown. The strip is maintained in close engagement with the rolls 12a by means of pressure rolls 12c which are positioned with respect to the rolls 12a so as to press the strip tightly thereagainst, and maintain the strip in close engagement therewith. In each vertical pass of the strip through the tank, there are anodes 13 positioned on both sides of the strip. Passage of current between the anodes and strip cathode and through the electrolyte results in the deposition of a metallic coating on the surfaces of the strip. By passing the strip vertically through the plating tank, the possibility of foreign matter and gases accumulating on either surface is minimized and a superior coated product is obtained.

As the strip emerges from the plating tank, and if it is desired to recover any electrolyte remaining on the surface thereof, it may be passed into and through a recovery apparatus 14, wherein it is subjected to sprays of a rinsing medium to remove traces of the electrolyte.

The coated strip next is subjected to a water rinsing operation, and, if desired, such rinsing operation may include a brushing action, whereby the surface may be brightened to any degree desired.

In order to produce strip free from drying stains, it is passed through the apparatus 16, wherein both of its surfaces are subjected to the action of steam sprays, not shown. The action of the steam upon the strip not only removes the last traces of foreign matter from the surface, but also heats the strip during its passage through the apparatus, so that as it emerges therefrom and comes into contact with the air, it dries immediately. Since the rinsing action is the result of condensation of the steam, this final rinse may be termed a pure water rinse and, as such, minimizes the drying stains on the surface of the strip

as it emerges from the steam bearing atmosphere in apparatus 16. While the strip is heated during its passage through the apparatus 16, the temperature attained by it is insufficient to change the physical characteristics imparted by the temper rolling operation. However, the temperature of the strip as it emerges from the apparatus 16 is approximately at the boiling point of water, and to protect the rubber covered forward 10 pulling drive bridle rolls 17, there is positioned between the exit end of the apparatus and the said bridle rolls 17, a blower 18, which directs air upon the surface of the strip to reduce its temperature prior to its passage through the said drive bridle rolls 17.

The strip leaves the drive bridle rolls 17 in a substantially untensioned condition, and in order to be conveyed therefrom and to finishing equipment, such as shearing and stacking devices, not 20 shown, the untensioned strip is caused to be passed over a bridge-like structure 19, which may be a roller bed wherein the rollers are freely rotated so as to insure passage of the strip thereover without injury to its surface or causing the 25 same to be buckled or kinked.

The foregoing general description is presented for the purpose of exemplifying a specific application or embodiment of the combined conveying and conductor rolls 12a, the particular construction of which forms the subject matter of the present invention, in order to show clearly just how these rolls are employed in service, and which is the inherent manner of use of this general type of rolls as is well known to the practical workers in the art.

Because of the conditions of service to which the rolls 12a are subjected, they must have, inherently, certain particular properties for satisfactory operation. It is to be noted that the strip 40 is passing continuously at high speed through the system, the strip, in practice, having a linear speed of many hundreds of feet per minute, and the rolls have, in reality, a dual function in that they both convey the strip being plated through 45 the electrolytic cell, and, at the same time, conduct current to the strip being coated, so that this strip forms the cathode in the plating tank and, as will become apparent from the foregoing description in connection with Figures 1 and 1A, 50 the rolls merely conduct current to the strip and enter in no way into the electrolytic action in the cell.

As has been mentioned above, such dual purpose conveyor and conductor rolls must have, inherently, particular properties for use in conveying the strip being coated through the electrolytic cell while conducting current to the strip.

Thus, as will be seen from Figures 1 and 1A, the strip being plated passes over several of the rolls 60 as it progresses through the plating tanks. As the strip travels through the electrolyte, it picks up some of the electrolyte, so that the combined conveyor and conductor rolls of the present invention must be sufficiently corrosion-resistant 65 to withstand the action of the materials present in the electrolyte, which may include, for example, sulphuric and phenolsulphonic acids.

Since some slippage between the rapidly moving strip and the rolls is unavoidable, it follows 70 that the surface of the rolls must be hard, as well as, resistant against corrosion by the electrolyte.

Additionally, since the edges of the strip may be burried, and since the strip is under tension as it 75 is conveyed by the rolls, the surface of the rolls

must be sufficiently hard to withstand scoring action of such burred edges.

A further inherent characteristic of the rolls is that the surface of the rolls should not become wetted easily by the electrolyte, since if the rolls were wetted easily, there would be an additional tendency of the surface of the rolls to become attacked by the electrolyte, with resulting deterioration and contamination of the roll surface. Moreover, easy wettability facilitates transfer of foreign material to the roll surface and makes cleaning of the roll more difficult. Thus, for example, the first roll of a series thereof, that is to say, the incoming roll on which the strip travels as it enters the electrolyte, this roll tends to become contaminated with iron compounds, preferably iron hydroxides, minute amounts of which are present in the water film carried by the strip following cleaning as the result of oxidation of the freshly pickled strip surface by the water. The rapidity with which the contaminating layer builds up and the facility with which it can be removed depends to a great extent on the ease with which the roll surface is wetted.

Wettability of the roll surface is also important as regards subsequent rolls in the series. In this case, however, the contaminating material is minute particles of the coating metal itself which are abraded from the coated strip when slippage between the strip and the roll occurs. Such particles become attached to the roll surface, and then themselves act to abrade more coating metal from the strip if the slippage continues. The adherence of the particles and the ease with which such particles are removed, depends upon the wettability of the roll surface. Hardness of the surface is also important in this respect since the cleaning must be done without damage to the roll surface, otherwise chances of abrasion of the coating metal are increased and the trouble aggravated.

Roughening of the roll surface, whether caused mechanically by corrosion, or the build-up of contaminating materials results in high spots which, in turn, become points of abnormally high pressure as the strip passes over the roll. Such high spots not only mar the strip with indentations and scratches, but because of the pressure, abnormally high current is transferred at these points, which condition generally results in arcing and at least in overheating of the strip at the points. The net result is areas which are burned or badly oxidized and which do not coat properly, the coatings being poorly adherent and faulty in appearance.

It is found in practice that a roll possessing the satisfactory mechanical and electrical properties can be obtained by applying a chromium surface to a copper roll, copper being a good conducting material, and the chromium facing having the requisite hardness, corrosion resistance, and wetting properties to give satisfactory results.

Each of the rolls 12a is composed of a suitable metallic cylinder 30, which preferably is a copper cylinder having a facing 32 of chromium thereon, which facing forms a chromium coating for the cylinder and imparts to the cylinder the above described advantages, and desirable properties. The roll is closed at its ends by steel end castings 34 which are extended into stepped hubs 36. A shaft 38 extends through the roll and hubs 36, the shaft 38 being preferably made in two complementary parts threadedly interconnected as indicated at 40. The shaft 38 is tapered towards its end to receive the collector rings or

drums 42 which have a driven fit with the shaft 38 and which are held in place by lock nuts 44 and 46, the lock nuts 44 being threaded on the shaft, as is indicated at 48, while the lock nuts 5 46 are threaded on the ends of the hubs 36, as is indicated at 50.

The end castings 34 are held in place by having a drive fit with the cylinder 30. The outer face of each of the end castings is provided with a layer of insulation 52 held in place by means of fasteners 54. The insulating disks 52 are sufficiently large to cover the ends of the cylinder 30 as well as the end castings 34, thereby protecting the operators of the apparatus from accidental shocks as well as protecting the ends of the roll assembly from damage. The inner surfaces of the end castings 34 are recessed adjacent to the shaft 38 for the provision of water-tight packing 56, which preferably is lead, for preventing leakage of water between the end castings and shaft.

In order to reinforce the cylinder 30 as well as to conduct current therefrom to the shaft 38 in a more efficient manner, the interior of the cylinder 30 is subdivided by a suitable number of metallic diaphragms 58, which are, like the cylinder 30, preferably composed of copper. The diaphragms 58 are provided with holes 60 for the passage of cooling water therethrough.

In order to introduce cooling water into the roll, the end portion 62 of the shaft 38 is provided with a bore 64 which is adapted to be connected with a suitable supply of water 65, and which communicates with radially extending openings 66, which inject water into the interior of the roll. Water passes from these openings through the holes 60 in the diaphragms 58, the diaphragms being welded to the shaft, as indicated at 68, to form a water-tight bond with the shaft. The holes 60 are disposed around the periphery of the diaphragm.

The end portion 70 of the shaft 38 is provided with an outlet pipe 72 which communicates with a bore 74 in the end portion 70 of the shaft. This bore 74 extends through the end of the shaft and is closed by a removable plug 76, if a water flinger 78 is employed, water then leaving the shaft 38, through radial holes 80 which communicate with the water flinger 78 which is enclosed in a housing 82. Glands 84 are provided to hold packing 86 in place. If the water flinger 78 is not used, the plug 76 may be removed and the end of the shaft connected to a suitable pipe connection.

The outlet pipe 72 is long enough to extend from the shaft 38 almost to the cylinder 30, so that the interior of the roll will be filled with cooling water.

The rolls are suspended from cross-beams such as indicated at 88, which cross-beams are positioned above the respective plating tanks and are suitably secured to the framework, not shown, which encloses the tanks. A portion of such framework is indicated by the beams 90 extending along the top portion of the tank, one of which beams carries a bracket arm 92 which supports the end portion 62 of the shaft 38 and defines a housing 94 for a water-tight swivel connection 96 between the water supply 65 and end portion 62 of the shaft. The cross-beams 88 are reinforced and held rigidly spaced apart by means of beams 98 extending longitudinally of the plating tanks and sufficiently above the tanks to accommodate the beams 88 which are welded to the beams 98.

The rolls 12a are suspended from the cross-beams 88 by means of stirrup-like brackets 100

through anti-friction bearings 102 in which the hubs 36 rotate. The bearings 102 are suitably fastened to the brackets 100 by means of bolts 104, for example, the brackets 100 being secured in turn to the underside of the cross-beams 88 by means of bolts 106. Brackets 100 are insulated from bearings 102 by suitable insulation as indicated at 105.

Also mounted on the underside of the cross-beams 88 is a pair of similar brackets 108 in which are mounted pivot pins 110 for the mounting arms 112 of the hold-down rollers 12c. These arms are somewhat sickle-shaped to hold the rolls 12c off center, the hold-down rolls holding the strip closely against the roll 12a for uniform electrical contact therebetween, the hold-down rolls acting on the strip by gravity, or if desired, suitable springs may be provided to increase the pressure of the hold-down rolls.

The cross-beam 88 also carries on its end the contact plates 114, which are connected electrically to the collector rings or drums 42 through collector brushes, not shown. The plates 114 are secured to the ends of the cross-beam 88 by means of bolts 116, or other suitable fastening means, a layer of insulation 118 being interposed between the plates 114 and the cross-beam 88. The bolts 116 are suitably insulated from the plates 114.

It is preferred to make the roll structure out of copper except for the steel end castings 34, which provide reinforcement for the roll and, together with the hubs 36, provide rigid mountings for the bearings 102. The shaft 38 preferably is a copper shaft and the diaphragms 58 similarly are made out of copper. These further reinforce the roller and provide good heat as well as current conducting paths between the shaft and the roller. The lead packing or washers 56 provide for expansion as well as prevent leakage. Cooling water is admitted to the interior of the roll through the bore 64 drilled in the shaft and through the holes 66 which are drilled radially into the shaft until they communicate with the bore 64. The outlet pipe 72 for the water extends inside the roll toward the periphery to a short distance therefrom, which in practice is about $\frac{5}{8}$ inch from the inside of the copper cylinder 30. The water leaves the shaft through radial holes 80 and bronze water flinger 78 enclosed in the housing 82, the glands 84, which hold the packing 86 in place and prevent leakage around the shaft. The water passes from housing 82 through discharge pipe 120.

The diaphragms 58 and the end castings 34 are turned for shrink and press fits in the copper cylinder 30 to assure good electrical contact. Additionally the copper diaphragms are welded to the shaft 38 as shown at 68, and to the inside of the copper cylinder 30 as is indicated at 122. The steel end castings 34 and the copper diaphragms 58 are designed with proper current carrying characteristics so that the diaphragms each carry about $\frac{1}{3}$ of the total current to the shell and each steel end casting carries about $\frac{1}{6}$ of the current. In this way, the maximum current is carried directly to the central portion of the roll where the greatest current density is required. The collector drums 42 are made preferably from copper, and they assure a large surface area of copper for the collector brushes. The collector brushes, not shown, are fastened to sickle-shaped copper members, not shown, carried by the copper plates 114. The collector drums 42 are pressed onto a tapered fit on the copper shaft to secure good

electrical contact, and are held in place by lock nuts 44 and 46.

The anodes 13 are composed of the metal being plated, e. g., tin, and are disposed on both sides of the moving strip being plated. Each series of anodes is suspended from a conductive bridge 124 which receives current from bus bars 126 adjacent to the top 128 of the plating tanks.

Sink rolls 12b are shown as being mounted on shafts such as 130, having suitable bearings 132. The sink rolls 12b are covered with rubber for insulation and for preventing marring the strip being plated. End insulation 52, covering the ends of the conductor rolls 12a, protect the rolls from damage during insertion of the anodes, or during other assembling of the equipment.

The chromium surface 32 is applied in any suitable manner, and it is found to constitute an excellent contact surface for the intended purpose.

In operation, the plating current passes from the anodes to the strip, thence to the surface of the combined conveyor and conductor roll, thence through the diaphragms 58 and end castings 34 to the shaft 38 and out by way of the collector drums 42, collector brushes, not shown, and contact plates 114.

It will be apparent from the foregoing that the electrical function of the conductor roll is to establish the rapidly moving strip as cathodically energizing the strip so that metal is plated on the strip as the strip passes through the electrolyte. Mechanically, the conductor roll serves to facilitate the movement of the strip through the system and to convey the strip through the plating cells. The chromium facing or coating 32 is applied so as to be bonded to the cylinder 30 with an integral bond.

The structure of the present invention may be assembled in various ways. For example, the shaft sections may be threaded together and the diaphragm members 58 inserted thereover and welded in place thereon and the outlet pipe 72 suitably secured. The resulting assembly then is inserted in the roll shell, which previously has had the chromium facing applied to it, and the diaphragms 58 are welded to the inner surface of the shell as shown in Figure 6. The lead packings 56 then are applied over each end of the shaft and placed around the shaft adjacent to the largest shoulders of the shaft. The end castings 34 with their integral hubs 36 then are placed over the ends of the shaft and brought up to the roll shell, after which they are pressed suitably into place, as by a hydraulic ram, for example, until the flanges 134 engage the shoulders 136, this action also tightly wedging the lead packings 56 in place to form water-tight seals between the end castings 34 and the shaft. The insulating facings 52 then are applied and fastened in place with screws 54. Lock nuts 46 then are threaded onto threads 50 of the hubs 36, and the collector drums 42 then are pressed onto the shaft and locked by means of the nuts 44 and 46. Finally, the water flinger assembly is applied and secured to the shaft, if such water flinger is to be used. Discharged water is led away from the roll and suitably disposed of. The hubs 36 are provided with flanges 138, which deflect any water leaking from and prevent this from coming into contact with current collector drums 42.

As will be seen, the internal construction of the roll is such that the cooling water is directed

continuously against the side areas of the roll which require maximum cooling.

We claim:

1. Apparatus for electroplating metal on a continuously rapidly moving strip of dissimilar metal, which comprises a combined conveyor and conductor roll for conveying the strip through an electroplating bath, the said roll also contacting and supplying electric current to the strip as it moves through the plating bath and making the said strip the cathode in the bath, the said combined conveyor and conductor roll comprising a hollow electrically conducting cylinder, a conductor shaft for mounting the cylinder, current conducting diaphragms between the cylinder and shaft in conducting relation therewith, the said diaphragms having a diameter equal to the inside diameter of the cylinder and being spaced equally along the shaft and cylinder and at equal distance within the ends of the cylinder, the said diaphragms uniformly distributing current over the entire cylinder, electrically conducting end closure members for the cylinder in tight engagement therewith and with the shaft, the said closure members being of less conductivity than the diaphragms, and forming auxiliary current conducting and distributing members cooperating with the diaphragms for uniformly distributing the current over the entire cylinder, the said closure members being extended into tapering hubs engaging the shaft, current collecting drums in tight engagement with the shaft, and means in the shaft for circulating cooling fluid through the cylinder.

2. Apparatus for electroplating metal on a continuously rapidly moving strip of dissimilar metal, which comprises a combined conveyor and conductor roll for conveying the strip through an electroplating bath, the said roll also contacting and supplying electric current to the strip as it moves through the plating bath and making the said strip the cathode in the bath, the said combined conveyor and conductor roll comprising a hollow copper cylinder, a copper shaft for mounting the cylinder, copper conducting members inside the cylinder and welded to the shaft and cylinder, the said members being copper diaphragms spaced equally along the shaft and cylinder and at equal distance within the ends of the cylinder, the said diaphragms being of the same diameter as the inside diameter of the cylinder, the said diaphragms being means for conducting major portions of current from the shaft to the cylinder and for uniformly distributing current on the said cylinder, steel end closure members for the cylinder tightly fitting into the cylinder and around the shaft, the said closure members cooperating with the diaphragms in securing uniform current distribution on the cylinder, each closure member conducting a less amount of current between the shaft and cylinder than do the diaphragms, the said closure members being extended into elongated tapering hubs engaging the shaft, copper current collective drums tightly mounted on the shaft, and locking means on the shaft and hubs for locking the drums in position on the shaft.

3. Apparatus for electrically energizing a continuously rapidly moving strip of metal, which comprises a combined conveyor and electrical contact roll for conveying the strip through an electrolytic bath, the said roll also contacting and supplying electric current to the strip as it moves through the plating bath and making the strip an electrode in the bath, the said com-

bined conveyor and contact roll comprising a hollow cylindrical roll body composed of high conductivity metal, a shaft for mounting the roll body, the said shaft being composed of high conductivity metal, spaced conductive diaphragm means in the roll body dividing the said body interiorly into a series of cooling compartments, the said diaphragm means having a diameter equal to the interior diameter of the roll body and welded to the shaft and to the roll body in intimate electrical connection with both the shaft and roll body, the said diaphragm means constituting the major conductive path for major portions of current between the shaft and roll body, means for conducting current to the shaft, electrically conductive end closure members for the roll body closely engaging the shaft and roll body, the said end closure members being less conductive than the diaphragm means but cooperating with the diaphragm means to assure uniform distribution of current on the roll body, means for circulating cooling fluid through the shaft, and means for maintaining each of the cooling compartments in the roll body continuously filled with continuously circulating cooling fluid.

4. Apparatus for electroplating metal on a continuously rapidly moving strip of dissimilar metal, which comprises a combined conveyor and conductor roll for conveying the strip through an electroplating bath, the said roll also contacting the strip and supplying electric current to the strip as it moves through the plating bath and making the strip the cathode in the bath, the said combined conveyor and conductor roll comprising a hollow cylindrical roll body composed of high conductivity metal, a facing on the roll body adapted to contact the strip and having a hardness substantially greater than the strip and the metal being plated onto the strip, a shaft for mounting the roll body, the said shaft being composed of high conductivity metal, means for conducting current to the shaft, spaced conductive diaphragm means mounted on the shaft in the roll body dividing the said roll body interiorly into a series of transverse cooling compartments, the said diaphragm means having a diameter equal to the interior diameter of the roll body and circumferentially engaging the roll body and welded to the shaft and to the roll body in intimate electrical connection with both the shaft and roll body, the said diaphragm means constituting the major conductive path for major portions of current between the shaft and roll body, electrically conductive end closure members for the roll body closely engaging the shaft and roll body, the said end closure members being less conductive than the diaphragm means, but cooperating with the diaphragm means to assure uniform distribution of current on the entire roll body, and means for maintaining each of the cooling compartments in the roll body continuously filled with continuously circulating cooling fluid.

5. Apparatus for electroplating metal on a continuously rapidly moving strip of dissimilar metal, which comprises a combined conveyor and conductor roll for conveying the strip through an electroplating bath, the said roll also contacting the moving strip and supplying electric current to the strip as it moves through the plating bath and making the strip the cathode in the bath, the said combined conveyor and conductor roll comprising a hollow cylindrical roll body composed of high conductivity metal, a facing on the roll body adapted to contact the strip and having a hard-

ness greater than the strip and the metal being plated onto the strip, a shaft for mounting the roll body, the said shaft being composed of high conductivity metal, means for conducting current to the shaft, spaced conductive diaphragm means mounted on the shaft in the roll body dividing the roll body interiorly into a series of transverse cooling compartments, the said diaphragm means having a diameter equal to the interior diameter of the roll body and circumferentially engaging the roll body and welded to the shaft and to the roll body in intimate electrical connection with both the shaft and roll body, the said diaphragm means constituting the major conductive path for major portions of current between the shaft and roll body, electrically conductive end closure members for the roll body closely engaging the shaft and tightly fitting into the roll body, the said end closure members being less conductive than the diaphragm means but cooperating with the diaphragm means to assure uniform distribution of current on the entire roll body, a fluid intake passage in the shaft extending from a point beyond the roll to a point within the roll adjacent to an end closure member for the roll body, fluid supply ports connecting the intake passage with the interior of the roll body, fluid passage ports through the diaphragm means adjacent to the roll body, an outlet pipe in the roll body extending from the shaft to a point adjacent to the roll body, the outlet pipe being positioned in the roll body adjacent to the end thereof opposite to the intake ports, and a fluid outlet passage through the shaft extending from the outlet pipe oppositely to the intake passage, the shaft being solid between the intake and outlet passages, the ports in the diaphragm means and the outlet pipe maintaining the entire interior of the roll body continuously filled with continuously circulating cooling fluid for preventing overheating of the roll.

6. An electrical contact roll for electrically energizing continuously moving metallic strip material passing over the roll in contact with a surface thereof, which comprises a hollow cylindrical roll body composed of high conductivity metal, a mounting shaft for the roll body, means for electrically energizing the shaft, electrically conductive end closure members for the roll body in close electrical contact with the shaft and roll body, diaphragms fixed to the shaft and to the roll body interiorly thereof, the said diaphragms defining the principal path of conduction of energizing current for the roll body, the said diaphragms being composed of a metal having higher electrical conductivity than the end closure members, the said diaphragms and end closure members cooperating to produce uniform current distribution on all of the roll body, and means for continuously circulating a cooling liquid through the interior of the roll body.

7. An electrical contact roll for electrically energizing continuously moving metallic strip material passing over the roll in contact with a surface thereof, which comprises a hollow cylindrical roll body composed of high conductivity metal, a mounting shaft for the roll body, means for electrically energizing the shaft, electrically conducting end closure members for the roll body in close electrical contact with the shaft and roll body, and diaphragms fixed to the shaft and to the roll body interiorly thereof, the said diaphragms defining the principal path of conduction of energizing current for the roll body, the said diaphragms being composed of a metal having higher electrical conductivity than the end

closure members, the said diaphragms and end closure members cooperating to produce uniform current distribution on the strip-engaging surface of the roll body.

5. Apparatus for electroplating metal on a continuously rapidly moving strip of dissimilar metal, which comprises a roll for conveying the strip through an electroplating bath and supplying electric current to the strip, said roll comprising 10 a hollow copper cylinder, a facing of chromium on the cylinder, a copper shaft for mounting the cylinder composed of tapering sections threadedly interconnected, means for conducting current to the shaft, reinforcing copper diaphragms within 15 the cylinder in tight engagement with the shaft and inner cylinder wall, the said diaphragms defining principal current supplying means for the cylinder for uniformly distributing major portions of current on the said cylinder, steel end closure members for the cylinder in close fitting engagement therewith and with the shaft and cooperating with said diaphragms for uniformly supplying and distributing current to the copper cylinder, a fluid intake passage extending through 20 a portion of the shaft from a point beyond the cylinder and communicating with the interior of the cylinder adjacent one end thereof, a fluid discharge passage extending through another portion of the shaft from within the cylinder to a point beyond the cylinder in a direction opposite to the fluid intake passage, a fluid discharge pipe opening within the said cylinder adjacent to an end thereof opposite to the fluid intake passage and extending to a point immediately adjacent to the cylinder, said pipe communicating with the fluid discharge passage in the shaft, and 25 passages in said copper diaphragms disposed adjacent the cylinder for passage of fluid therethrough, said cylinder thereby being swept interiorly by continuously circulating cooling fluid.
- 40 9. Apparatus for electroplating on a continuously rapidly moving strip of dissimilar metal, which comprises a roll for conveying the strip through an electroplating bath and supplying 45 electric current to the strip, said roll comprising a hollow electrically conducting cylinder, a conductor shaft for mounting the cylinder, diaphragms between the cylinder and shaft, said diaphragms being uniformly spaced along the 50 shaft and cylinder and having a diameter equal to the inside diameter of the cylinder, thereby tightly engaging the cylinder and dividing the cylinder interiorly thereof into a series of transverse cooling compartments, said diaphragms being 55 of high electrical conductivity for conducting the major portions of current from the shaft to the cylinder while uniformly distributing the current on the cylinder, electrically conducting end closure members for the cylinder in tight engagement with the shaft and cylinder and being or less electrical conductivity than said diaphragms, the end closure members cooperating with said diaphragms for uniformly supplying the cylinder with current and for uniformly distributing 60 the current on the cylinder, current collecting instrumentalities tightly mounted on the shaft, and locking means on the shaft and end closure members for securing the current collecting instrumentalities in position on the shaft.
- 65 70 10. A roll for conveying metal strip and conducting electric current thereto comprising an electrically conductive shaft, an electrically conductive hard faced cylinder, electrically conductive closures at the cylinder ends, and electrically

13

conductive diaphragms intermediate the length of the cylinder, said closures and said diaphragms mounting said cylinder on said shaft, the electrical conductivity of said diaphragms being appreciably greater than that of said end closures to furnish a substantially uniform current density on the wall of said cylinder.

EARLL R. MUDDIMAN.
